UNITED STATES PATENT OFFICE.

JOHN L. C. HEINZ, OF CHICAGO, ILLINOIS.

CASEMENT-WINDOW HINGE WITH AUTOMATIC LIFTING AND LOCKING MEANS.

Application filed April 13, 1925. Serial No. 22,512.

To all whom it may concern:

Be it known that I, JOHN L. C. HEINZ, a citizen of the United States, and a resident of the city of Chicago, county of Cook, and 5 State of Illinois, have invented certain new and useful Improvements in Casement-Window Hinges with Automatic Lifting and Locking Means, of which the following is a specification.

10 My invention pertains to a casement window hinge with automatic lifting and locking means, and has for its object to provide such a hinge which will enable the casement window to be pushed down behind the window stool, to make the window rain-storm proof, and which is provided with means 15 acting automatically for locking said window in such closed position to prevent the same from being pried or jimmied open 20 from the outside.

Another object is to provide such a hinge with means for automatically lifting the window above the window stool when the locking means has been released, so that the 25 window may be readily swung and opened inwardly.

Another object is to construct a hinge of this kind in such manner that the parts may be readily disassembled and assembled to 30 adapt the hinge for use on either the right side or the left side of the window.

Other objects will appear hereinafter.

The invention consists in the combinations and arrangements of parts hereinafter 35 described and claimed.

The invention will be best understood by reference to the accompanying drawings forming a part of this specification, and in which,

40 Fig. 1 is an elevational view of a casement window showing my improved hinge applied thereto,

Fig. 2 is a vertical sectional view taken along line 2—2 on Fig. 1,

45 Fig. 3 is an enlarged elevational view of the hinge positioned on a window,

Fig. 4 is a cross sectional view taken on line 4—4 of Fig. 3,

50 Figs. 5 and 6 are detail views of the two main parts of the hinge, disassembled,

Fig. 7 is a cross sectional view taken on the line 7—7 of Fig. 5, and

55 Fig. 8 is a detail view of the sleeve or guard member for the lifting spring shown in Fig. 3.

In the drawings my improved hinge is illustrated in connection with a casement window including the window parts or sashes 11 and 12 which are swingably mounted, by means of my hinges, in the window frame 13, to engage inwardly of the transom 14 and to be movable downwardly behind the window stool 15, thus preventing the rain from coming in under the casement window.

My improved hinge, illustrated in these drawings, comprises two main parts 16 and 17, the part 16 having pintle barrels 18 adjacent its ends and providing an extended space therebetween, while the part 17 has a pintle barrel 19 mounted between said barrels 18 by means of a pintle 20, which may include a fixed head 21 and a removable head 22, as indicated in Fig. 5, the pintle barrel 19 being shorter than the distance between the pintle barrels 18, thus permitting the hinge part 17 to be moved longitudinally on the part 16 and on the pintle 20. The hinge part 17 preferably includes a part 17' arranged substantially at 75 right angles to the main part 17, thus permitting the main part 16 to be mounted on the inward side of the window frame while the part 17' is fastened on the inner face of the window sash, as shown in the drawings. 80 The parts 16 and 17' are provided with suitable openings for receiving screws 23 and 24 respectively to fasten the hinge parts on the window frame and on the window sash as indicated. The hinge part 17 with 85 the attached window sash is movable on the pintle and along the hinge part 16 to lower the window back of the window stool 15, and is movable upwardly to the upper part of the pintle to clear the window stool and 90 enable the window to be swung inwardly over said stool.

Means is provided for locking the window with the attached hinge part 17 in its lowered or closed position, and this means is arranged to engage the movable hinge part 17 and hold it in its closed position. The construction of the locking means preferably includes a finger 25 mounted on the hinge part 16 by means of cleats or curved lugs 26 engaging in openings 27 provided adjacent the end of hinge part 16, and a spring 28 is mounted on hinge part 16 to press finger 25 against pintle 20 and into the path of pintle barrel 19, thus automatically locking the 105 110

pintle barrel 19 with its hinge part 17 and the attached window sash in the lowered or closed position, a curved or raised portion 25' being provided on said finger 25 to be engaged for 5 pressing the finger backward away from pintle 20 to permit return movement of pintle barrel 19. A set of openings 27 and a spring 28 are provided adjacent each end of hinge part 16, thus enabling the finger 25 to 10 be readily removed from the position shown in Fig. 5 and to be placed in the lower position, thereby enabling the hinge to be used on the right-hand side of the window and to bring the locking finger at the upper end of 15 the hinge when the hinge has been reversed. Means is also provided for automatically lifting the hinge part 17 with its attached window sash upwardly when the locking finger 25 is withdrawn from its locking position, and this means preferably includes a 20 coil spring 29 mounted on pintle 20 above the lower pintle barrel 18 and preferably provided with a collar 30 at its upper end to form a pivot seat for the swinging movement of pintle barrel 19 thereon. This spring is of the required strength and tension to automatically lift the hinge part 17 with the particular window sash attached thereto, as soon as the locking finger is 25 released. A guard member or sleeve 31 is mounted over spring 29 and collar 30, and is provided with a slot 32 for receiving the rib or flange portion 33 adjacent pintle barrel 19 of hinge part 17 when said hinge part 30 with the attached window is moved downwardly into its closed position. A slot 34 is provided at the lower end of sleeve 31 to receive the rib or flange portion 35 of hinge part 16, and this sleeve thereby provides 35 means for positively locking the hinge part 40 17 against swinging movement on the hinge part 16 when said part 17 is lowered and the locking finger 25 extends above the same in its locking position. The slot 34 is slightly 45 offset from slot 32, and a similar slot 34' is offset in the other direction from slot 32, thus enabling the sleeve to be used reversibly, adapting the entire hinge for use on the right hand side of the window as well 50 as on the left-hand side, said slot 34' receiving the rib 35 at the opposite end of hinge part 16, when the hinge is used on the right-hand side of the window, and suitable turn-bolt 36 and locking member or eye member 55 37 being used in the customary manner, and a nut 38 holds sleeve 31 in position.

It is apparent from the above disclosure 60 that the hinge is constructed symmetrically and is readily reversible, by merely unthreading the head 22 and nut 38 from the pintle 20 and withdrawing said pintle, then removing sleeve 31 and spring 29, also unhooking the locking finger 25 from the openings 27, and placing the curved lugs 26 of 65 the locking finger in the opposite openings

27 and moving the hinge part 17 towards the opposite end of the hinge part 16, then replacing the spring 29 and sleeve 31 with pintle 20 in the positions reversed from that shown in Figs. 5 and 6, thus adapting the 70 hinge for use on the right-hand side of the window. It is also apparent that the hinge part 17 may be pressed downward against the action of the spring, and the attached window therewith lowered into its closed position to engage outwardly of the window stool 15, and that at the same time the spring 28 will automatically press the finger 25 into locking position to retain the window positively in its closed and locked position, said 75 hinge being furthermore retained in such locked position by the aid of the sleeve 31 with its slots 32 and 34; and it is also apparent that by pressing the finger 25 outwardly, the spring 29 will automatically raise the hinge part 17 with the attached window upwards to clear the window stool 15 and permit inward swinging of the window. This improved hinge is 80 preferably used as the lower part of each 85 window sash only, while the locking finger 25 and the sleeve 31 with the spring 29 are left off from the hinges at the upper parts of the window sashes, thus enabling each 90 sash to be opened with the use of one hand 95 for the locking finger.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 100 the appended claims.

Having described my invention what I claim as new and desire to secure by Letters Patent is:

1. A casement window hinge comprising 110 a part fastenable on the window sash and a part fastenable on the window frame, the hinge part with the window sash being movable vertically on the other part and frame, spring means for automatically moving said 115 window sash and attached hinge part on the frame and other hinge part, a collar on said spring means to act as a pivot seat for swinging the hinge part with the window thereon, and a spring pressed locking member for automatically holding said window and hinge part in the lower closed position.

2. A hinge comprising a part with spaced 120 pintle barrels, a pintle in said barrels, another hinge part with a pintle barrel movable between the spaced barrels longitudinally on said pintle, a spring on said pintle for automatically moving the movable barrel longitudinally of said pintle, a guard sleeve on said spring mounted against 125

swinging movement on said first hinge part and having a slot for receiving the second hinge part, and locking means for locking the second hinge part in said slot and to prevent swinging movement thereof on the first hinge part.

3. A hinge comprising a part with spaced pintle barrels, another hinge part with a pintle barrel movable longitudinally on said first hinge part, a pintle removably mounted in said pintle barrels, a spring removably mounted on said pintle to automatically move the second hinge part longitudinally on the first part, and locking means removably mounted on said hinge for retaining the movable hinge part locked in a certain position on the first hinge part, said hinge having its parts constructed symmetrical and reversible to adapt the hinge for use at either the right side or left side of a window.

4. A hinge comprising a part with spaced pintle barrels, a pintle in said barrels, another hinge part with a pintle barrel movable between the spaced barrels longitudinally on said pintle, a spring on said pintle for automatically moving the movable barrel along said pintle, and a guard sleeve around said spring being provided with an upper slot for receiving the movable hinge part to hold the same against movement on

the other hinge part and with a pair of lower slots for selectively receiving the other hinge part, said slots and the entire hinge being constructed symmetrical to adapt the hinge for use at either the right side or the left side of a window.

5. A hinge comprising a part with spaced pintle barrels, a pintle in said barrels, a second hinge part with a pintle barrel movable between the spaced barrels longitudinally on said pintle, a spring on said pintle for automatically moving the movable barrel longitudinally on said pintle, a guard sleeve on said spring provided with slots for selectively mounting it against swinging movement on said first hinge part and having a slot for receiving the second hinge part to hold the same against movement on the first hinge part, a collar on said spring to act as a pivot seat for swinging the movable hinge part thereon, and a spring pressed locking finger for locking the second hinge part in said slot and in position on the first hinge part, said hinge having its parts constructed symmetrical and reversible to adapt the hinge for use at either the right side or the left side of a window.

In testimony whereof I have signed my name to this specification.

JOHN L. C. HEINZ.
